Attorney

UNITED STATES PATENT OFFICE.

HARRY WASHINGTON WATSON, OF MEMPHIS, TENNESSEE.

WRENCH.

1,330,151.

Specification of Letters Patent. Patented Feb. 10, 1920.

Application filed March 29, 1919. Serial No. 286,055.

To all whom it may concern:

Be it known that I, HARRY WASHINGTON WATSON, a citizen of the United States, and a resident of Memphis, in the county of 5 Shelby and State of Tennessee, have invented certain new and useful Improvements in Wrenches, of which the following is a specification.

My invention relates to improvements in 10 wrenches, and more particularly to that type of wrenches wherein different sized sockets or spanners are used for various sized nuts.

An object of my invention is to provide 15 a wrench structure by which nuts may be quickly run up or down on a bolt and then tightly locked in place.

Another object is to provide a wrench that can be used with various sized nuts.

With these and other objects in view, my 20 invention consists in certain novel features of construction, arrangement and combination of parts, as will be hereinafter fully described and pointed out in the claims, reference being had to the accompanying drawings, in which—

Figure 1 is a side elevation of my wrench device as in use,

Fig. 2 is a top plan view of the head and handle of the same,

Fig. 3 is a vertical section of the head shown in Fig. 1,

Fig. 4 is a bottom plan view of the wrench with lower collar removed,

Fig. 5 is a top plan view of the lower collar,

Fig. 6 is a perspective view of a collet used with my device,

Fig. 7 is a similar view of a cap socket member,

Fig. 8 is a perspective view of a spring used to actuate a dog or pawl,

Fig. 9 is a perspective view of one of the dogs or pawls.

Referring more specifically to the drawings, A represents a wrench head or casing which is made of steel or other suitable material, the handle B being preferably integral therewith and projecting off to one side thereof. The head is suitably cored out 45 to form a lower chamber C, and having a circular opening D through the upper wall thereof.

The lower face of the head is cored out to form suitable spaces E—E diametrically op-

posite each other within which are pivotally 55 mounted the dogs or pawls F which are exactly alike and provided with noses G—G, the purpose of which will be later described.

At points diametrically opposite each other and in a plane perpendicular to the 60 plane of the spaces containing the dogs, the lower face of the head is cored out to form the T-shaped spaces H—H, the stem portion of the T extending through the side walls of 65 the head and constituting the stem of another T-shaped slot I in the side wall, that is a double bayonet joint slot, as shown in Figs. 1 and 3.

A collar or face plate J having a central 70 opening K somewhat smaller than the lower open end of the case is provided on its inner face with diametrically oppositely disposed studs L—L having outwardly projecting lugs M—M at their upper ends which lugs 75 project up into vertical portions N of the double bayonet slot and are then turned with the collar to occupy the horizontal portion of said slot I.

A collet O is seated on this collar and held in place thereby, the collet having a 80 central opening P the shape and approximately the size of the nut to be operated on. The outer wall of collet O is provided with notches o to receive the ends of the dogs F, while the upper face of the collet 85 is provided with ribs Q arranged in pairs at right angles to each other. This collet with the turning member R constitute the socket for the wrench, it having a central opening corresponding in shape and size to 90 the central opening of the collet, and is interlocked therewith by the pairs of grooves S engaging the ribs Q on the collet. A collar T provided with a central noncircular opening U projects from the upper face of 95 the member R which collar passes through and has a rotating fit in the central opening D through the upper wall of the head.

To keep the dogs or pawls F in active and operative position, that is, to force their 100 pointed noses into the notches in the sides of the collet, I provide plate springs F having one end embedded in the lower part of the head and the free end bearing against the backs of the dogs.

The various instrumentalities of the wrench are assembled in the following manner, assuming that they have already been 105

separately manufactured: The collet having the desired central opening is placed on the collar *J* in proper relative position. The cap socket *R* is then superposed on the 5 collet, the ribs and grooves interlocking; these three members are then engaged with the head by passing them into the cored out lower end, the lugs *L* entering the vertical portions of the bayonet slots and the collar 10 *T* on the cap socket *R* passing through the upper opening in the head or casing. The collar *J* is then turned to the right, the edge of the same being milled or knurled for this purpose, the noses of the dogs being 15 forced into the notches *o* in the collet, and the lugs moving into the right hand portion of the horizontal part of the bayonet slot, until it reaches the closed end thereof. The wrench is now ready for use and the 20 socket opening used to engage the nut is adapted to slight variations in size of nuts. For instance, one socket will operatively fit a one-inch, a three-quarter, and seven-eighths nut, and each collet used will allow 25 for three sizes of nuts.

In the non-circular opening in the top of the cap socket is to be placed one end of a crank *V*, such end being non-circular (preferably rectangular) while the opposite end 30 of the crank is provided with a handle.

The manner of using the wrench is as follows:—The collet and cap socket is fitted over the nut which is on a bolt or stud, by holding the handle member in one hand, and 35 with the other hand the non-circular end of the crank is inserted in the socket in the collar of the cap socket, and the crank given a quick turn; this will cause the nut to run rapidly up on the bolt or stud against the 40 object carrying the bolt, and then the handle of the wrench is swung down to tighten the nut against the object.

To run the nut off quickly, the collar is turned to the left which will carry the lugs 45 into the opposite ends of the horizontal slots of the bayonet joint and reverses the dogs with respect to the notches and collet; the crank is then turned in the reverse direction whereupon the nut will rapidly run up and 50 off the bolt.

From the above it will be seen that I produce a wrench which can be used for quickly running up a nut and securely locking it in place, and one in which the nut can be run off with equal rapidity, without the necessity of the workman having to put his hand or hands on the nut.

I claim:

1. A wrench comprising a shank or handle 60 and a head having a cored chamber in its lower end, and a circular opening through its upper end, a rotary socket member rotat-

ably mounted in said chamber, and a removable collar engaging the lower end of said head and supporting the rotatable socket 65 member therein, and means carried by the socket member whereby the same may be rotated independently of the head and the supporting collar.

2. A wrench comprising a rigid head and handle extending transversely therefrom, the lower end of said head having a cored out chamber and bayonet slots in its side walls at diametrically opposite points, an annular collar at the lower end of said chamber, lugs 75 carried by said collar and engaging said slots, a notched collet having a nut socket and supported on said collar, a spring controlled dog carried in said cored chamber and adapted to engage the said notched collet, 80 a cap socket mounted on said collet and in interlocked relation therewith, a collar carried by said cap socket and fitted within the circular opening in the top of the head, said collar having a non-circular socket in 85 its upper portion, and a crank having a non-circular end adapted to fit in said non-circular socket, whereby the interlocked cap socket and interlocked collet may be rotated independently of the wrench head. 90

3. A wrench comprising a rigid head and a handle extending transversely therefrom, the lower end of said head having a cored out chamber, and bayonet slots in its side walls at diametrically opposite points, an 95 annular collar at the lower end of said chamber, lugs carried by said collar and engaging said slots, a notched collet having a nut socket and supported on said collar oppositely positioned spring controlled dogs 100 carried in said cored chamber and adapted to engage said notched collet, a cap socket mounted on said collet and in interlocked relation therewith, a circular collar carried by said cap socket and fitted within the circular opening in the top of the head, said 105 collar having a non-circular end adapted to fit in said non-circular socket, whereby the interlocked cap socket and collet may be rotated independently of the wrench head. 110

4. A wrench comprising a shank or handle and a head, said head having a cored chamber in its lower end and a circular opening through its upper end, a socket member rotatably mounted in said chamber, a collar member carried at the lower end of said head and supporting the rotatable socket member, said collar member removably held to the lower end of the head by bayonet joint connection, and means carried by the 115 socket member whereby it may be rotated independently of the head and supporting collar. 120

HARRY WASHINGTON WATSON.
